HAIR CURLER CLAMPING BOBBIN

Aram Teopilian, Brooklyn, N. Y.

Application July 22, 1947, Serial No. 762,629

5 Claims. (Cl. 132—40)

1

This invention relates generally to hair curling devices, and more particularly to a hair curler clamping bobbin of improved construction.

In the curling of hair, and particularly in the production of so-called "permanent waves," the hair of the user is wound upon some bobbin-like object and subjected to the action of heat, chemicals, or moisture, or combinations of these. In order to produce a desirable result, it is necessary that the hair be fixed in position while it is subjected to the waving treatment. Furthermore, it is necessary that a large number of individual locks of the user's hair be wound.

It is therefore among the objects of the present invention to provide novel and useful hair curling clamping bobbins which are convenient to use being quickly manipulatable from an open to a closed position or vice versa.

Another object herein lies in the provision of a hair curler bobbin which may be composed of relatively rigid material so that the same does not become undesirably distorted in use.

Another object herein lies in the provision of structure of the class described which is light in weight.

A still further object herein lies in the provision of means for the escapement of moisture or fumes produced in the hair coils during the waving treatment.

A feature of the invention lies in the absence of springs composed of metal which may lose their resiliency owing to heating and fatigue thereof and the absence of porous resilient parts composed of rubber or the like which are deleteriously affected by heat or chemicals and which thereby lose their resiliency and low absorbent qualities.

Another object herein lies in the provision of hair bobbin structure wherein the compressor latch element utilizes the resiliency of the coiled hair of the user for maintaining the same in a closed position.

A still further object lies in the provision of hair bobbin structure wherein the range of movement of the movable end plate may be amplified so as to accommodate a wider range of hair quantity treated by a single hair curling element, thereby enabling use of the device by persons having a relatively low degree of experience or skill in hair curling.

These objects and other incidental ends and advantages will more fully appear in the progress of this disclosure and be pointed out in the appended claims.

In the drawings in which similar refer-

2

ence characters designate corresponding parts throughout the several views:

Fig. 1 is an elevational view of a hair curler clamping bobbin showing an embodiment of the invention in a closed position thereof.

Fig. 2 is an end elevational view as seen from the plane 2—2 on Fig. 1.

Fig. 3 is a plan view seen from the plane 3—3 on Fig. 1.

10 Fig. 4 is an elevational view corresponding generally to Fig. 1, but on a reduced scale and showing the device in an open position thereof.

Fig. 5 is an enlarged fragmentary horizontal sectional view, partly in elevation, as seen from the plane 5—5 on Fig. 1.

15 Fig. 6 is a view in perspective of the embodiment shown in Fig. 1.

Figs. 7, 8 and 9 are an elevational view, a perspective view, and a sectional view (plane 9—9 on Fig. 7) respectively, of a second embodiment of the invention; while Figs. 10, 11 and 12 are an open elevation, a closed elevation (reduced), and an end view, respectively, of a third embodiment, whose axle element is shown in detail

25 elevation in Figure 13.

20 In accordance with the invention, the hair curler clamping bobbin, generally indicated by reference character 10, includes broadly an axle element 11, a first or stationary end plate 12, a second or movable end plate 13, and a compressor latch element 14. The various parts may be made of any suitable material, and I prefer to make them of molded synthetic resin which is relatively stable in shape, substantially non-porous, substantially chemically inert with respect to the waving solutions and materials used in the permanent waving operation, and which is relatively light in weight. The use of materials which are light in weight make the present bobbins comfortable to wear even when a large number of them are used for a particular coiffure.

25 The axle element is preferably generally rod shaped and includes an inner portion 15 and an outer portion 16. The inner portion is of greater diameter than the outer portion. The outer portion 16 is bifurcated to form the legs 17 and 18 having the slot 19 therebetween.

30 The stationary end plate 12 is secured to the outer end of the inner portion 15 in any suitable manner or may be cast integral therewith as shown. The end plate 12 is preferably in the form of a disc having a periphery 20 and a plurality of venting orifices 21.

35 The inner portion 15 has a hollow bore 22,

55

and is provided with a plurality of radially disposed venting orifices 23. At the juncture of the inner portion 15 and the outer portion 16, there is an annular shoulder 24.

The movable end plate 13 is preferably substantially identical with the stationary end plate 12, except that it is provided with a central orifice 25 so that it is slidably axially along the outer portion 16. The plate 13 includes a periphery 26 and a plurality of venting orifices 27.

The compressor latch element 14 is in the form of a lever having a cam surface 28, and a latch member 29. While I have shown the element 14 as having an opening 30 and a brace 31, where desired, the opening 30 may be omitted. The brace 31 permits the portion of the element 14 having the cam surface 28 to be made relatively small in section, and where the same is made of more rigid material or of heavier cross section, the brace 31 may be omitted. The cam surface 28 may include a low dwell portion 32, a rise 33, and a high dwell portion 34. The low dwell portion 32 is preferably close to the axis of rotation 35 of the compressor latch element 14, the latter being pivotally mounted between the outer ends of the legs 17 and 18 in a suitable manner as by the use of the pin 36 which may be a force fit in said legs. This permits the movable end plate 13, when the parts are in the position shown in Fig. 4, to be removed from the stationary end plate 12, a maximum distance. The rise 33 may have a substantially uniform radius about the point 37 which is displaced from the longitudinal axis of the axle element 11, said axis intersecting the axis 35, referred to above. The high dwell portion 34 is preferably flat and tangentially disposed with respect to a circle having the axis 35 as its center. Thus, the imaginary radius extending from the axis 35 and with which the high dwell portion 34 forms a substantially right angle, is spaced from another imaginary radius extending from the axis 35 and passing through the point 37 previously described. This construction and arrangement of the parts causes the rise 33 to have an eccentric action going beyond a dead center in reaching a closed position of the compressor latch element 14. While I have shown the high dwell portion as being relatively planar and in contact with the outer surface of the movable end plate 13 along a substantial area of the latter, this provides additional support for the end plate 13, but only a small part of the high dwell portion is required, said part being indicated by reference character 60. The part 60 is closer to the axis 35 than is the high point 40 on the rise 33.

The operation of my hair curler clamping bobbin is a simple and convenient matter. All of the necessary parts are so connected that one cannot be misled with respect to the others and all can be grasped with a single hand. In operation the device is opened to take the position shown in Fig. 4 and the hair is wound about the axle element 11, between the end plates 12 and 13. After a particular lock of hair has been so wound, the latch member 29 is grasped as a handle and is rotated in a clockwise direction as viewed in Fig. 4. The cam rise 33 comes into action and forces the end plate 13 toward the end plate 12 thereby compressing the coiled hair. The highest point 40 (Fig. 1) of the rise 33 passes by the portion of the outer surface of the end plate 13 contacting by the cam rise with a passing dead center action, whereupon the high dwell portion 34 contacts the said outer surface

of the end plate 13. Simultaneously with the contacting of the dwell portion 34 against the outer surface of the end plate 13, the surface 41 of the latch member 29 contacts the peripheries 20 and 26. The parts of the device 10 will now appear as shown in Fig. 1. The hair because of its resiliency now exerts a force against the inner surface of the movable end plate 13, pressing the end plate 13 against the high dwell portion 34 thereby maintaining the device 10 in a latched condition. The hair 50 now compactly wound may be subjected to any desirable waving treatment and where moisture or gases are given off during the process, the same may escape through the orifices 21, 23 and 27. After the waving process is completed, the latching member 29 may be conveniently grasped and the element 14 swung about the axis 35 to the starting position. The shoulder 24 acts as a detent to prevent the end plate 13 from approaching the end plate 12 too closely when the bobbin is empty of hair and permits the easy manipulation of the plate 13 away from the plate 12 when the element 14 is in its open position (Fig. 4).

Turning now to the second embodiment of the invention illustrated in Figs. 7-9 inclusive, for the purpose of avoiding needless repetition, parts corresponding to the first embodiment, are given the same reference characters, with the addition of a prefix "1".

The second embodiment differs from the first principally in the wider range of movement afforded by the movable end plate 113. The axle element is slotted more deeply so that the high dwell portion 134 may enter said slot even when the pin 136 is in the notch 162, that is to say, nearest the stationary end plate 112.

The opposed portions of the bifurcated end of the axle element are provided with the notches 160, 161, and 162 which are inclined in the direction of the free end of said axle. Thus, by the provision of a plurality of the notches 160-162, the fulcrum of the compressor latch element 114 is made adjustable so that adequate compression may be made upon the lock of hair which has been wound between the end plates 112 and 113, even where there is substantial variation in the bulk of the hair between the end plates. The resilient expansion of the hair against the movable end plate 113, not only causes the compressor latch element to stay closed, in a manner previously described, but also tends to maintain the pin 136 seated within the particular notch into which it has been placed.

While I have shown only three notches, obviously, any desired number may be used producing a corresponding variation in the number of adjustments obtained.

Turning now to the third embodiment of the invention illustrated in Figures 10 to 13 inclusive, for the purpose of avoiding needless repetition, parts corresponding to prior embodiments are given the same reference characters, with the addition of the prefix "2".

The third embodiment differs from the first embodiment principally in the wider range of movement afforded by the movable plate 213. The axle element 211 is slotted more deeply so that the high dwell portion 234 may enter said slot even when the pin 236 is in the notch 272, thereby moving the plate 213 closely toward the plate 212.

As contrasted with the second embodiment, the notches for adjustment are provided in the compressor latch element 214, said notches 270, 271

and 272 extending off the slot passageway 273, instead of in the axle element.

The axle element 211 may be a form of split rivet which is provided with a reduced portion 274 upon which the relatively stationary end plate 212 is mounted. The head 275 when peened over also supports the retainer element 276 having the two end hooks 277 and 278. These hooks may be used to engage adjoining or adjacent hair strands to retain the device 210 in position upon the user's head, with the plate 212 toward the scalp. In order to permit the latch member 229 to close when the notches 270 or 271 are engaged by the pin 236, the hook 277 may be provided with an indentation 279, or the retainer element may be rotatably mounted with some friction in the joint. It may then be rotated as indicated for example by the dot-dash lines on Figure 12.

As seen in Figures 10 and 11, the latch element 214 is in the form of a lever having an edge cam surface 223 and a latch member 229. The cam surface 228 may include a low dwell portion 232, a rise 233, and a high dwell portion 234. The operative effect of these parts will vary, depending upon which notch of the notches 270, 271 and 272 has been selected by the user, as the axis or rotation of the latch element 214. Since each of the notches extends obliquely toward the cam portions 233 and 234, the resilient pressure of the user's hair presses the movable plate 213 against the portion 234, which tends to move the latch element 214 in a direction axially of the axle element 211 and away from the stationary plate 212. This tends to retain the pin in the closed end of the particular notch in which it is then located. All this causes the latch member 229 to be moved toward engagement with the peripheries of the end plates 212 and 213.

I wish it to be understood that I do not desire to be limited to the exact details of construction shown and described, for obvious modifications will occur to a person skilled in the art.

I claim:

1. Hair curler clamping bobbin construction comprising: a first end plate; and an axle element connected to said first end plate; a second end plate movable on said axle element; a cam engageable with said second end plate and acting to move the second end plate toward the first end plate; said cam being detachably pivotally mounted upon said axle element at a plurality of locations on said cam.

2. Hair curler clamping bobbin construction comprising: a first end plate; an axle element secured to said first end plate, said axle element having a pivot; a second end plate movable on said axle element; and means to move the second end plate toward the first end plate, said means including a cam having a plurality of notches selectively engaged with said pivot.

3. A structure as claimed in claim 2 with a retainer element on the first end plate.

4. A hair curler clamping bobbin comprising: a first end plate having a first periphery; a second end plate having a second periphery; means movably connecting said first and second end plates; a compressor latching element pivotally mounted on said means and contacting a portion of said second end plate, movement of said latching element acting to shift the position of said second end plate with respect to said first end plate; said compressor latching element having a latching member which contacts said first and second peripheries when said bobbin is in closed position thereof.

5. A hair curler clamping bobbin comprising: a first end plate having a first periphery; a second end plate having a second periphery; an axle element movably connecting said first and second end plates; a compressor latching element pivotally mounted on said axle element and contacting a portion of said second end plate, movement of said latching element acting to shift the position of said second end plate with respect to said first end plate; said compressor latching element including a cam surface actuated by movement of a latch member; said last mentioned latch member contacting said first and second peripheries when the bobbin is in a closed position thereof.

ARAM TEOPILIAN.
